UNITED STATES PATENT OFFICE

159,537

CHAIR OR THE LIKE

Julius P. Sacks, Chicago, Ill.

Application March 26, 1949, Serial No. 1,631

Term of patent 7 years

(Cl. D15—1)

To all whom it may concern:

Be it known that I, Julius P. Sacks, a citizen of the United States and a resident of Chicago, county of Cook, and State of Illinois, have invented a new, original, and ornamental Design for a Chair or the like, of which the following is a specification, reference being made to the accompanying drawings, forming a part thereof.

Fig. 1 is a side view in elevation of a chair or the like, showing my design;

Fig. 2 is a front view thereof in elevation;

Fig. 3 is a rear view thereof in elevation; and,

Fig. 4 is a top plan view thereof.

I claim:

The ornamental design for a chair or the like, substantially as shown.

JULIUS P. SACKS.
